UNITED STATES PATENT OFFICE.

STANLEY KRUK, OF CLYMER, PENNSYLVANIA, ASSIGNOR TO KRUK PERCUSSION FUSE COMPANY, OF LATROBE, PENNSYLVANIA.

PERCUSSION-FUSE.

1,335,003.

Specification of Letters Patent. Patented Mar. 30, 1920.

Application filed January 20, 1919. Serial No. 272,087.

To all whom it may concern:

Be it known that I, STANLEY KRUK, a citizen of the United States, residing at Clymer, in the county of Indiana and State 5 of Pennsylvania, have invented certain new and useful Improvements in Percussion-Fuses; and I do declare the following to be a full, clear, and exact description of the invention, such as will enable others skilled 10 in the art to which it appertains to make and use the same.

This invention relates to percussion fuses, and relates more particularly to certain improvements on the device covered by my 15 Patent No. 1,232,814, issued July 10, 1917.

One object of this invention is to greatly simplify the construction and minimize the cost of manufacture of articles of this character.

20 Another object is to greatly increase the efficiency or certainty of explosion upon being operated.

Another object is to materially increase the degree of safety and ease of operation.

25 Other objects and advantages may become apparent to persons who read the following details of description in connection with the accompanying drawings in which:

Figure 1 is an elevational view, illustrating my improved percussion fuse connected to a rope or cord whereby it is operated.

Fig. 2 is an enlarged longitudinal sectional view of my improved percussion fuse.

30 Fig. 3 is a transverse sectional view along the line 3—3 of Fig. 2.

Fig. 4 is a transverse sectional view along the line 4—4 of Fig. 2.

Referring to these drawings in detail, in 40 which similar reference characters correspond with similar parts throughout the several views, the device comprises a tubular body 5 which is preferably gradually tapered toward one end and provided with an annular or radial flange 6 at its other end.

A cap 7 having a peripheral inwardly extending flange 8 engages with the flange 6 so as to securely unite the cap with the tubular body, and this cap is preferably 50 cavo-convexed so that a space is provided between the inner parts of the cap 7 and flange 6. This provides oppositely disposed seats 9 on which a holding element 10 normally rests. This holding element 10 preferably 55 comprises an end portion of a length

of wire which extends through an opening 11 in the cap 7 and may be attached to a rope or heavy cord as indicated at 12 in Fig. 1 for a purpose hereinafter explained.

A plunger or striker 13 is apertured at 14 60 to receive the wire holding element 10, the latter being engaged with the plunger 13 at a point between the seats 9, and this engagement of the plunger with the holding element 10 also provides a seat for the 65 upper end of a spring 15. The lower end portion of the plunger 13 is provided with oppositely extending studs 16 which provide a seat for the lower end of the spring 15, and these studs or this spring seat 16 70 extends approximately to two opposite sides of the tubular body 5 so as to co-act with the said opposite sides in guiding the plunger in its path of movement centrally of the tubular body 5. The top of the cap 75 7 is provided with a central recess 17 in which the upper end of the plunger 13 rests and is held in the central position with relation to the tubular body 5.

Within the lower or constricted end of 80 the tubular body 5 is secured a mass 18 of combustible or explosive material such as blasting glycerin or dynamite, and upon the top or inner surface of this combustible or explosive mass is secured a cap 18^a of fulminating material which may be composed of nitroglycerin or other high explosive. An anvil or metal rod 19 has its major portion embedded in the explosive mass 18, a small end portion of the rod 19 extending into the 85 fulminating cap and being united with the latter so as to more securely unite the fulminating cap with the explosive mass 18. In constructing a device of this kind, the rod or anvil 19 may be united with the fulminating material, prior to the assembling 90 of the device, by touching one end of the anvil against a mass of fulminating material so that a portion of the mass adheres to the anvil, and the elements 18' and 19 become a unit so that excessive convenience 95 and accuracy are assured in assembling the device. The anvil or rod 19 is disposed at the end of the path of movement of the striker 13, so that the latter will strike the 100 fulminating cap adjacent to and directly over the end of the anvil 19, thereby increasing the efficiency or certainty of the explosion of the fulminating cap.

In using this improved percussion fuse, 110

the same is embedded in a charge of powder, dynamite or other blasting material, the wire 10 extending out through the latter, and after the charge of blasting material is tamped in the usual manner, the rope is pulled with sufficient force to draw the wire 10 through the aperture or opening 11 and out of engagement with the striker 13; whereupon, the spring 15 expands until it is 5 stopped by the cap 7, and the plunger or 10 striker 13 is then impelled by the spring and guided by the lateral projections 16 to strike the fulminating cap directly over the upper 15 end of the anvil 19. This causes the fulminating cap to explode, and its explosion causes the explosive mass 18 to explode and transmit its explosive force and heat to the charge of blasting material.

Because of the holding element of the 20 wire 10 being supported at two points, and the plunger 13 being supported thereby between these two points, the wire 10 may be 25 relatively light and flexible as compared with that of my prior patent in which the plunger-holding member is supported at one point only. Obviously, this relation of 30 parts not only absolutely prevents the plunger from being accidentally released from its holder, but it also renders the device more easily operated because of the wire 10 being more flexible.

Although I have described this embodiment of my invention very specifically, it is not intended to limit this invention to 35 these exact details of construction and arrangement of parts, but I am entitled to make changes within the scope of the inventive ideas disclosed in the foregoing description and following claims.

40 What I claim as my invention is:

1. A percussion fuse comprising a tubular body, explosive material in said tubular body, a spring-pressed plunger in said tubular body and operatable to strike said explosive material, and a length of wire nor-

mally supported by opposite sides of said body and engaged with said plunger between said opposite sides and being movable out of engagement with said plunger to permit said plunger to be operated by its 50 spring.

2. A percussion fuse comprising a tubular body, an explosive mass therein, a fulminating cap on said explosive mass, an anvil embedded at least partly in said explosive mass and united with said fulminating cap so as to constitute both an anvil and a secure anchorage for the fulminating material, and a striker in the tubular body and operable to strike the fulminating cap at 55 a point alined with said rod.

3. A percussion fuse comprising a tubular body, an explosive mass therein, a fulminating cap on said explosive mass, an anvil embedded at least partly in said explosive mass and extending into and united with said fulminating cap, and thus securing the latter in position on the explosive body, and a striker in the tubular body and operable to strike the fulminating cap at 60 a point adjacent to the said anvil.

4. A percussion fuse comprising a tubular body having a radial flange around one end, a cap engaged with said flange and closing said end of the tubular body and being 65 spaced from the tubular body to provide seats on opposite sides of said tubular body, a spring - pressed plunger in said tubular body, a holding member normally on said seats and engaging with said plunger between said seats and thus securely holding said plunger against the force of the plunger-spring, and explosive material in position within said tubular body to be struck by said plunger, said holding member being 70 movable for releasing said plunger and permitting its actuation by said plunger-spring.

In testimony whereof I have hereunto set my hand.

STANLEY KRUK.
